WATER CLOSET CONSTRUCTION

William E. Sloan, River Forest, Ill.

Application May 13, 1935, Serial No. 21,097
Renewed April 25, 1938

13 Claims. (Cl. 4—70)

This invention relates to water closet constructions and has for its object to provide a new and improved device of this description.

In hotels, apartments and many other buildings where space is a factor and cost must be considered, the flush valves are not concealed by accessible corridors or other ways, and hence are exposed in the room, presenting a lot of surface joints, threads, couplings, etc., that are unsightly even when they are kept clean. They are, however, seldom kept clean and on account of the location they are sprayed with urine, which will ruin even chrome plate, until finally all of these metal parts make a very unsightly and objectionable appearance. This invention has as a further object to provide a water closet and flush valve construction which shall be free from these objectionable features.

The invention has as a further object to provide a water closet construction wherein there is a bowl and flush valve, and a housing for protecting the flush valve which joins with the bowl.

The invention has as a further object to provide a water closet construction comprising a bowl, a flush valve and a housing for the flush valve so arranged as to provide for both horizontal and vertical errors in the location of the supply and waste openings with relation to each other or the floor or the partition wall.

The invention has as a further object to provide a water closet construction having a bowl and the flush valve and means for protecting the flush valve and associated parts.

The invention has as a further object to provide a housing for the flush valve and associated parts which can be easily removed for access to the parts by simply lifting the housing.

The invention has as a further object to provide a one piece housing for the flush valve and associated parts.

The invention has other objects which are more particularly pointed out in the accompanying description.

Referring now to the drawings,

Fig. 1 is a view showing one form of the invention;

Fig. 2 is an enlarged plan view of a portion of Fig. 1, parts being broken away;

Fig. 3 is an enlarged sectional view with parts broken away;

Fig. 4 is a sectional view taken on line 4—4 of Fig. 3;

Fig. 5 is a sectional view taken on line 5—5 of Fig. 3;

Fig. 6 is a view showing a modified construction;

Fig. 7 is a sectional view taken on line 7—7 of Fig. 6;

Fig. 8 is a view showing a further modified construction;

Figs. 9 and 10 are front and side views of the bowl of Fig. 1 in position before the installation of the flush valve, showing the dimensions which are variable and which are taken care of by the present construction;

Figs. 11, 12 and 13 show different forms of the housing fastening device; and

Fig. 14 is a fragmentary view showing the flush valve handle construction.

Like numerals refer to like parts throughout the several figures.

Referring now to the construction shown in Figs. 1 to 5, wherein one form of the invention is illustrated, there is shown a bowl 1 supported upon the floor 2. There is a waste pipe 3 into which the bowl discharges, and a supply pipe 4 which supplies water to the bowl through a flush valve. This supply pipe 4 projects through the wall 5 and connects in any suitable manner with a flush valve 6, see Figs. 3 and 4. Any suitable connection may be used. I prefer to have an adjustable connection, such as shown in Fig. 4, wherein there is a fitting 6a attached to the end of the pipe 4, which may be provided with a shutoff valve, and a pipe section 7 connected with the fitting, and an elbow 8 to which the pipe section 7 is connected, said elbow being connected with the flush valve by a ball and socket joint in any suitable manner.

As herein shown, there is a ball member 9 on the end of the elbow 8 which fits into a suitable ball receiving socket in the inlet member 10 of the flush valve, and the connecting member 11 which connects the elbow with the flush valve. The flush valve may be of any suitable type, and I have shown a construction where the main valve 12 of the flush valve is set into operation by tilting the stem 13 of the auxiliary valve, this stem being tilted by the actuating member 14 which is actuated by the handle 15, the movement of the handle in any direction causing the agitating member 14 to be moved to contact the auxiliary valve stem 13 so as to tilt it and cause the main valve to open and discharge water into the bowl. The handle is arranged so that it can operate the actuating member 14 by contact and does not require a positive connection. This is arranged by providing the handle with the enlarged part 15a and the actuating member

14 at its end with an enlarged portion 14a which is pressed outwardly by a spring 14b. The part 15a has an annulus 15b which engages a projection 15c on the housing so as to hold the handle in position. When the housing and handle are in position, the part 15a on the inner end of the handle simply contacts with the part 14a and has no positive connection with it. Figs. 4 and 5 clearly show the construction.

The water from the flush valve is discharged through the discharge pipe 16 into the bowl. I prefer to place in this discharge pipe a vacuum breaking device which is located in a chamber 17 in proximity to the flush valve. This chamber has a water inlet 18 and a water outlet 19 and an air inlet 20. Pivotaly mounted in the chamber is a lever 21, one end carrying a valve 22 adapted to control the air inlet, and the other end carrying the control member 23 opposed to the water inlet. This member 23 is arranged so that when in its closed position it does not entirely close the water inlet, but will permit a leakage back through it of a small amount of air to destroy any vacuum that may be produced in the supply pipe. The parts are arranged so that the end of the lever carrying the valve 22 is heavier than the other end, so that when no water is flowing the valve 22 will be open so that the air inlet 20 will be open, the parts being in the position shown in Fig. 4.

When the flush valve is operated, the water strikes the controlling member 23 and moves it to its open position and at the same time, moves the valve 22 to its closed position so as to completely close the air inlet. After the flush has ceased the parts move back to the position shown in Fig. 4, where the air inlet is open. This air prevents a vacuum from forming in the discharge pipe and when there is a vacuum in the water supply pipe, air from the air inlet passes through the water inlet past the control member 23 in a direction opposite to that of the water, and this air enters the water supply pipe to destroy any vacuum therein and to also act as a cushion to the water when it again enters the supply pipe and prevents noise which would occur if the vacuum were not broken.

This device, therefore, performs both functions of preventing back siphonage and preventing objectionable noise when the water rushes back into the water supply pipe.

A cover or housing 24 is provided for the flush valve and associated parts. This housing is open at the back and at the bottom, so that it can be located firmly against the wall and in order that it can be readily removed to get at the flush valve and associated parts. This housing is made in a single piece and is attached to the wall so that it can be easily removed by simply lifting it upwardly. This housing may be made of any suitable material, preferably of metal enameled so that its exterior surface will exactly match that of the closet bowl in connection with which it is used. This housing is preferably provided with a plurality of rubber cushions 25 which contact with the closet bowl. It is also provided with a rubber bumper 26 with which the closet seat or cover contacts when in an open position. This housing is provided with an opening 27 through which the operating handle for the flush valve projects.

The housing, which is preferably of a single piece open at the back and bottom, is held in its proper position over the flush valve by suitable fastening devices connected with wall. In Figs.

11, 12 and 13 there is illustrated various holding devices for holding the housing in position. In Fig. 11 there are the holding members 28 and 29 fastened to the wall, the two members being separate. In Fig. 12 these members are connected together by a connecting member 28a so that they constitute a single piece. In Fig. 13 there is attached to the wall, in addition to the holding members 28 and 29, the holding members 30 and 31 which also act as centralizing members. These members may be connected directly to the wall or to a member 32, which is attached to the wall. The housing has an engaging member 33 which fits in between the members 30 and 31. The housing also has engaging members 34 and 35 which engage the holding members 28 and 29. It will be seen that to place the housing in position it is only necessary to place it over the flush valve and against the wall and then move it down so that the engaging parts on the housing engage the holding parts on the wall. The holding parts on the wall are fastened to the wall in such a position and at such a height as to compel the housing to rest on the closet bowl and maintain a position centrally horizontal with relation to the closet bowl. The holding parts on the wall and the engaging parts on the housing are so related as to cause the back edge of the housing to be drawn tightly against the wall. The housing itself may be entirely supported by the holding device on the wall or may rest upon the top of the bowl, but it should be in such a position as not to leave any space between its edge and the bowl. It will further be seen that to remove the housing it is only necessary to lift it up. When so lifted, the handle 15 and the part 15a go with the housing. The housing is gravitationally held in position.

In the building of buildings when the plumber does his roughing in, that is installs the supply and waste openings for the water closets, the condition of the building construction is such that it is difficult, if not impossible, for him to determine exactly where the finish line of the floor or the wall will be in the finished building, and as the position of the supply and waste openings for the bowl made at the time the roughing in is done cannot be materially altered after the floors and walls are finished, it is necessary that the connections to the bowl and associated parts allow for both horizontal and vertical errors in the location thereof. It is also necessary that the housing that is to fit against the wall, and also lap over on the closet bowl, must be capable of compensating for errors in the distance the waste opening is located from the partition. In Figs. 9 and 10 there is illustrated the three variable distances which must be compensated for by this construction. These variable distances, which vary with different installations, are the horizontal distance between the back of the bowl and the wall, as shown at A in Fig. 10, the vertical distance between the water supply pipe and the water inlet 1a for the bowl, indicated at B in Fig. 10, the water inlet 1a of the bowl being centrally located, and the third variable distance is the horizontal distance between the water supply pipe and the bowl inlet 1a, indicated at C in Fig. 9. These indicated distances show substantially the maximum variations found in actual practice and which must be compensated for by the present invention.

It will be seen that by means of the present construction the connection made to the supply pipe 4, when it is considerably above or below

or to the right or the left of its correct position, still allows the flush valve to be connected by means of the union ball joint. For variations in height it is only necessary to shorten or lengthen the pipe section 7 and the plumber can easily cut these sections of the desired length. The vertical flush connection also permits variation in height between the flush valve and the closet bowl by means of the slip joint connection provided on the flush elbow, that is by making the pipe 1b shorter or longer as required. The horizontal flush connection permits variation between the flush valve and the closet bowl by the slip joint connection provided in the spud or inlet 1a of the bowl, that is by lengthening or shortening the pipe 1b. These adjustments are necessary to permit the flush valve to be placed in suitable or preferred positions with relation to the housing 24. This is due to the fact that a flush valve must be in a fairly definite relation to the housing in order that the handle will operate the flush valve, and the housing must be in a central position with relation to the bowl. The bowl 1 must always be located in a fixed position with relation to the opening of the waste pipe 3. Bowls are usually provided with a projection 38, Figs. 1 and 10, at the end of the discharge passageway 40 which fits into the opening of the waste pipe 3, and this compels the bowl to always be in the same position with relation to the waste pipe. If the plumber has made an error in locating this opening of the waste pipe, the bowl may be located at various distances from the wall 5 and this must be compensated for or taken care of by the housing. In order to arrange for this, the housing is provided with an overlapping lower end 41 where it rests on the bowl, and in order to obtain this overlap it is necessary that the closet bowl project some distance back of the seat posts 42.

Ordinarily the top of the bowl does not extend much beyond the seat posts 42, and in that event there may not be a sufficient extension to compensate for the various positions of the bowl. I may provide bowls with a sufficient extension 43, as shown for example in Figs. 1, 2 and 3, this extension being integral with and part of the bowl and formed when the bowl is manufactured, thereby providing the bowl with a rearwardly extending part which extends rearwardly from the usual rear edge 43a, illustrated by the dotted line in Fig. 3. When the bowl does not have such an extension, I then provide a separate extension 44, see Fig. 6, which overlaps the back of the bowl and which is held in position by the seat posts 42, this extension projecting rearwardly a sufficient amount to insure the proper overlap of the casing and the extension for all the varying distances between the wall and the bowl. This extension 44 is preferably made of metal and arranged to have the same coloring as the bowl.

In Fig. 8 I have shown what is called a wall bowl 45, the bowl being provided with an extension 46 which is fastened by fastening devices 47 to the wall 48. In this case the supply pipe 49 and the waste pipe 50 are located one above the other and their openings are at the face of the wall and the bowl discharge is connected with the opening of the waste pipe and the flush valve with the opening of the supply pipe.

It will thus be seen that the housing can be cheaply made, as it is made of one piece, and that this single piece housing extends from the wall to the bowl so as to conceal the flush valve and

associated parts. It will further be seen that the housing has no attaching devices which must be removed in order to remove it from the flush valve, but that the housing can be easily and quickly removed by lifting it up, and that the flush valve handle goes with the housing when the housing is in position and actuates the flush valve when out of position, either up or down or sidewise, and can be quickly and easily replaced by placing it in position and then moving it downward. It will further be seen that this housing completely covers and protects the flush valve and associated parts and yet can be easily and quickly removed to gain access to them for any reason. It will further be seen that the housing can be made to harmonize with the bowl and that being of a single piece, it presents a pleasing appearance. It will further be seen that since the housing fits up against the wall, it is stable and leaves no unsightly space between it and the wall. It will further be seen that this housing may be properly placed in position centrally with relation to the bowl, concealing the flush valve and connections when there are both horizontal and vertical variations in the relation between supply pipe, flush valve and the closet bowl.

I have described in detail a particular construction embodying the invention, but it is of course evident that the parts may be varied in many particulars, and parts omitted and others added, without departing from the spirit of the invention, as embodied in the claims hereto appended, and I therefore do not limit myself to the particular construction shown.

The use and operation of my invention are as follows:

After the building is finished the bowl is placed with the projection 39 in the opening of the waste pipe 3 forming the usual gasket connection, and the holding member for the housing is fastened to the wall 5 so as to bring the housing in the proper position with relation to the bowl. The flush valve and discharge pipe 16 are connected 45 with the bowl and the supply pipe 4 connected with the flush valve, the ball joint permitting this connection for all the variations of the position of the supply pipe. The housing is then slipped down in position over the holding member 28 until it rests upon the top of the bowl. The part 14a then comes opposite the handle 15 so that when the handle is actuated the parts 14a and 14 will be moved inwardly so that the part 14 will engage the stem 13 of the tilting valve to operate the flush valve. It will be seen that by having the enlarged parts 14a and 15a which engage each other, the handle and the actuating part 14 may be considerably out of alignment in any direction, and yet the handle when moved will actuate the actuating part 14. This compensates for any errors which may be made in centrally locating the flush valve. This housing completely covers and protects the flush valve and associated parts and forms an extension of the bowl which covers these parts, the housing and the bowl forming a unitary construction in appearance and effect.

It will further be seen that I have here a construction which automatically adjusts itself and compensates for the errors of the plumber in locating the supply pipes and the waste pipes and which provides a means so that the assembly can be made rigid without throwing the finished fixtures out of alignment for all these various positions of the openings of the supply pipe and waste pipe.

I claim:

1. A water closet bowl construction comprising a water closet bowl adjacent to a wall, a supply pipe adjacent to said wall, said water closet bowl being provided with supply and waste openings, a flush valve adjacent to said wall, connections between said flush valve and said supply pipe and water closet bowl, a one piece housing extending from the wall to the bowl and covering the flush valve and associated parts, and a holding device on the wall open at the top, bottom and one side and an engaging member on the housing which projects into the open side of the holding member and which holds said housing in position.

2. A water closet bowl construction comprising a water closet bowl adjacent to a wall, a supply pipe adjacent to said wall, said water closet bowl being provided with supply and waste openings, a flush valve adjacent to said wall, adjustable connections between said flush valve and said supply pipe and water closet bowl, a one piece housing, open at the back, extending from the wall to the bowl and covering the flush valve and associated parts, said housing being provided with a handle opening in its side, and means for operating said flush valve through said handle opening.

3. A water closet bowl construction comprising a water closet bowl adjacent to a wall and having a rearwardly extending part, a supply pipe adjacent to said wall, said water closet bowl being provided with supply and waste openings, the supply opening extending laterally into the bowl below the top thereof, a flush valve adjacent to said wall, connections between said flush valve and said supply pipe and water closet bowl, a housing extending from the wall to the rearwardly extending part of the water closet bowl, a portion of said housing lapping over a portion of said rearwardly extending part of said bowl, said housing covering the flush valve and associated parts and a connection from the flush valve to said supply opening projecting through the bottom of said housing and below the lower end thereof.

4. A water closet bowl construction comprising a water closet bowl adjacent to a wall, said water closet bowl having a rearwardly extending part, formed with a substantially flat surface at the rear of the seat, a supply pipe adjacent to said wall, the water closet bowl being provided with supply and waste openings, a flush valve adjacent to said wall, connections between said flush valve and said supply pipe and water closet bowl, a housing, open at the back, extending from the wall to the rearwardly extending part of the bowl, a portion of said housing extending over the flat surface of the rearwardly extending part of said bowl and covering the flush valve and associated parts, and a holding device on the wall comprising two separated holding members and two separated engaging members near the middle of the housing projecting inwardly and engaging said holding device on the wall to hold the housing in position.

5. A water closet bowl construction comprising a water closet bowl adjacent to a wall, said water closet bowl having a rearwardly extending part, added thereto, but integral therewith, a supply pipe adjacent to said wall, said water closet bowl being provided with supply and waste openings, a flush valve adjacent to said wall, adjustable connections between said flush valve and said supply pipe and water closet bowl, a housing ex-

tending from the wall toward the bowl, and having a portion which projects over a portion of the rearwardly extending part of said bowl, means for gravitationally holding said housing in position to cover the flush valve and associated parts, and means for centrally mounting said housing with relation to said bowl, so as to cover said flush valve and associated parts for a series of different positions of the waste pipe and supply pipe, with relation to each other and the wall.

6. A water closet bowl construction comprising a water closet bowl adjacent to a wall, a supply pipe adjacent to said wall, a waste pipe adjacent to said wall, said water closet bowl being provided with supply and waste openings, a flush valve adjacent to said wall, a housing extending from the wall to the bowl, and means for centrally mounting said housing with relation to said bowl, so as to cover said flush valve and associated parts for a series of different positions of the waste pipe and supply pipe, with relation to each other and the wall.

7. A water closet bowl construction comprising a water closet bowl adjacent to a wall, a supply pipe adjacent to said wall, a flush valve connected with said supply pipe and with said bowl, a housing extending from the wall to the bowl and covering said flush valve and associated parts, and an operating device connected with the housing and disconnected from the flush valve, but adapted to operate the flush valve when the housing is placed in position.

8. A water closet bowl construction comprising a water closet bowl adjacent to a wall, a supply pipe adjacent to said wall, a flush valve connected with said supply pipe and with said bowl, a single piece housing extending from the wall to the bowl and covering said flush valve and associated parts, and means projecting through an opening in the side of the housing for operating the flush valve from the exterior of the housing when the flush valve is displaced vertically or horizontally from its central position in said housing.

9. A cover or housing for concealing the supply connections located between a wall and the rear of a water closet, comprising a hollow upright structure having the back and bottom open to facilitate placement and removal, and having a base portion which extends forward from the front face of the structure a substantial distance to enable the front of the extended base to overlap the rear of the water closet.

10. A cover or housing for the plumbing connections located between a wall and a water closet, comprising a hollow body with open back and bottom to facilitate placement and removal, said housing having a front face lying substantially parallel to the open back thereof, and having a base portion integral therewith, extending out in front of the said front face to enable the housing to extend from the wall and overlap the top of a water closet located further from the wall than the distance between the back of the housing and the said front face thereof.

11. A water closet bowl having a ledge at the rear thereof with upright hinge-bolt openings through the ledge, said ledge extending back from the said openings, at the width which it has at the openings, for a distance greater than the usual variations in the distance between the bolt openings of an installed bowl and the finished surface of a wall at the rear of the bowl, whereby a supply connection cover of a given size

may extend from the finished wall surface and overlap the ledge in uniform width in the various positions of the installed bowl relative to the wall, and a horizontal supply opening entering said bowl below said ledge, whereby the ledge is kept free to permit its being overlapped by said cover in the various distance relationships between the finished wall and the installed bowl.

12. In combination, a water closet bowl having a ledge comprising a rear extension of the top surface of the bowl, a supply opening entering said bowl below said ledge, supply fittings for leading a water supply to the said supply opening, said ledge being free for a distance at the rear thereof equal to or greater than the usual variations in the setting of closet bowls with respect to the surface of a finished wall located to the rear thereof, and a cover for concealing the

supply fittings, said cover being of such dimensions that it extends from the finished wall surface and overlaps the rear extremity of the top surface of said ledge when the bowl is located a maximum distance from the wall, whereby the cover overlaps successively larger portions of said ledge when the bowl is located at successively smaller distances from the wall.

13. In combination, a cover formed to conceal and protect a flush valve, an actuating device for said flush valve, said cover having a hole therethrough of sufficient size to permit said actuating device to pass through the cover from the inside, and an enlarged portion on the inner end 15 of said actuating device of sufficient size to prevent said actuating device from slipping out through said hole.

WILLIAM E. SLOAN.
